US00D661598S

(12) **United States Design Patent**
Battisti

(10) **Patent No.:** **US D661,598 S**
(45) **Date of Patent:** **** Jun. 12, 2012**

(54) **TUBE APPLICATOR**

(75) Inventor: **Peter D. Battisti**, Alpharetta, GA (US)

(73) Assignee: **Chemence Medical Inc.**, Alpharetta, GA (US)

(**) Term: **14 Years**

(21) Appl. No.: **29/387,598**

(22) Filed: **Mar. 15, 2011**

(51) **LOC (9) Cl.** **09-01**

(52) **U.S. Cl.** **D9/724**

(58) **Field of Classification Search** D9/434-436, D9/452-454, 723-729; D24/112, 113, 115, D24/127, 129, 133, 145; D28/7, 88, 89; 221/64, 65, 135, 208, 278, 282; 222/105, 222/394, 402.1, 402.15, 546

See application file for complete search history.

(57) **CLAIM**

The ornamental design for a tube applicator, as shown and described.

DESCRIPTION

FIG. 1 is an isometric view of the invention.

FIG. 2 is a front view of the invention.

FIG. 3 is a rear view of the invention.

FIG. 4 is a right side view of the invention.

FIG. 5 is a left side view of the invention.

FIG. 6 is a top view of the invention; and,

FIG. 7 is a bottom view of the invention.

1 Claim, 7 Drawing Sheets
